CLAIM

The ornamental design for a support stand, as shown and described.

DESCRIPTION

FIG. 1 is a perspective view of a support stand showing my design.

FIG. 2 is a front elevational view thereof.

FIG. 3 is a rear elevational view thereof.

FIG. 4 is a left-side elevational view thereof.

FIG. 5 is a right-side elevational view thereof.

FIG. 6 is a top plan view thereof.

FIG. 7 is a bottom plan view thereof; and,

FIG. 8 is a perspective view of the support stand being applied to a display.

The broken lines in FIGS. 1 through 8 are included for the purposes of illustrating environment only and form no part of the claimed design.
